SLIDE FASTENER

Louis W. Schaaff, Jackson Heights, N. Y., assignor
to Waldes Koh-I-Noor, Inc., Long Island City,
N. Y., a corporation of New York

Application August 4, 1941, Serial No. 405,423

5 Claims. (Cl. 24—205.5)

This invention relates to improvements in slide fasteners and more particularly to improved self-locking sliders therefor.

The present invention contemplates an improved self-locking slider of more or less standard design employing front and rear plates integrally connected by a bridging connector portion, and which in operation spreads the disengaged fastener elements fanwise. While suggestions to this end have been heretofore advanced, such have not proved commercially practical, with the result that sliders of the so-called standard design usually employ extraneous locking means which add to the overall bulk of the slider and are moreover unsatisfactory to a degree, due to the likelihood of their impairment when garments to which the fastener is applied are subjected to rough treatment in cleaning, ironing and the like.

Accordingly, one of the main objects of the invention is to provide an improved, commercially practical, and highly effective slider of the self-locking type and which employs a slider body of standard design.

The invention further aims to provide a self-locking slider of the stated character which is readily releasable, irrespective of whether or not the fastener stringers are under longitudinal or lateral stresses and which further requires no specialized manipulation of a pull tab or locking lever to effect release.

Another object of the invention is to provide a self-locking slider which may be constructed in quantity and assembled by existing automatic and semi-automatic assembling machines, whereby the improved slider may be put into immediate production without requiring substantial retooling for its manufacture.

The present invention further contemplates and provides a slider which while following the standard design therefor, nevertheless employs constructional features making the slider substantially crush proof to forces which would destroy the usefulness of standard sliders made by the known practices.

Other objects will be in part obvious from the annexed drawing and in part hereinafter indicated in connection therewith by the following analysis of the invention.

In the drawing—

Fig. 1 is a plan view of a portion of a slide fastener employing the standard design, self-locking slider of the present invention.

Fig. 2 is a longitudinal section through the slider illustrated in Fig. 1.

Fig. 3 is a face view of the slider blank in accordance with the present invention prior to final assembly.

Fig. 4 is an edge view of the blank illustrated in Fig. 3, with one side flange being broken away.

Fig. 5 is a side view of a slider in accordance with the invention following final assembly.

Fig. 6 is a section through the slider taken on a line corresponding to line 6—6 of Fig. 3.

10 Fig. 7 is a section through the slider taken along a line corresponding to line 7—7 of Fig. 3, spaced fastener elements within the slider body being illustrated.

Fig. 8 is a detail illustrating the preferred form of securing rivet.

Fig. 9 is a detail illustrating a modified form of rivet.

In the drawing, wherein like reference characters designate like parts throughout the several views, the slider S of the present invention is shown as associated with conventional interlocking or fastening elements 10, 11 arranged in row formation along the edges of opposed stringers 12, 13, the latter being in turn secured along the edges of an opening formed in a garment or like article which is adapted to be closed upon interlocking or meshing of the fastening elements. It is to be understood that the invention is not limited to the use of fastener elements as shown, the latter being merely suggestive of slide fastener elements of conventional construction.

The slider S is adapted to embrace the fastener elements in known manner and operates, when moved in one direction, generally upwardly, to progressively force the elements into interlocking engagement, and when moved in the opposite or downward direction, to disengage the fastener elements.

40 The slider S forming the subject matter of the present invention is formed from a blank of the character illustrated in Figs. 3 and 4. As shown, the blank is formed integral from a single piece of sheet stock to provide slider plates 16, 17 of generally bell-shaped contour, and a connecting waist portion 18. Each of the plates 16, 17 is provided with marginal side flanges 20, 21, and with each slider plate having bell-shaped contour, the flanges 20, 21 of a plate extend straight-

45 way for a substantial distance from one end thereof, whereupon the flanges diverge outwardly, and terminate in straightway end portions adjacent the waist-like connecting portion 18 of the blank.

50 In assembly operation, the plates 16 and

17 are bent to extend parallel, with the narrowed waist portion 18 forming an integral U-shape connecting bridge therebetween. By reference to Figs. 5, 6 and 7, the depth of the side flanges 20, 21 of the plates are such that when the blank is bent to U shape, the related flanges on each side of the body are spaced to provide slots along each side of the slider body for the reception of the stringers 12, 13.

While the slider body so far described is of generally standard design or contour, it differs from sliders made in accordance with the known practices by providing a novel form of separator which functions both as a divider for the fastener elements and as a spacer and support for the slider plates 16, 17. To this end, each plate portion of the blank has formed therein to extend from the relatively under face thereof an integral separator half-section of elliptical shape, the elliptical half sections 25a, 25b having their major axes coinciding with the longitudinal axis of the blank. Each separator section is of a depth half that required for the completed wedge, and its end face is formed flat to provide an abutment surface for the flat face of the companion section. By reference to Figs. 2, 5, 6 and 7, it will be seen that upon assembly of the blank, the separator sections 25a, 25b are in registry and bear against each other to provide a full depth separator generally designated 25 which is operative to perform the dual functions as aforesaid. The separator sections are each pierced to provide a rectangular rivet opening 26.

Preferably the blank is formed complete in a multiple-step die which in one step forms the blank with side wings which provide the side flanges, and in another die-forming step forms in the blank the two separator half-sections 25a, 25b, and simultaneously therewith bends the wings to provide the marginal side flanges aforesaid. The separator half-sections are punched to provide the rivet openings 26 either during the blanking out operation or in a subsequent forming operation. For final assembly, a rivet 30, as illustrated in Fig. 8, is inserted into the aligned rivet openings 26 of the separator sections, and upon upsetting the ends of the rivet, the slider plates 16 and 17 are securely disposed in spaced parallel relation. Preferably, the relatively outer faces of each of the blank plates is provided during forming of its separator half-section with a countersunk recess 31 in one of which the enlarged head 32 of the rivet 30 is adapted to seat. Thus, not only is firm seating of the rivet head against the outer face of the countersunk recess obtained upon the final assembly, but also, due to the countersinking of the plates as aforesaid, a slider body of minimum thickness is provided.

To further decrease the thickness of the slider body, the rivet head 32 is provided with an offset hook-like extension 33 adapted to curve over and secure the pintle portion of a pull tab 34 against the outer face of the relatively front plate of the slider.

By reference to Fig. 9 wherein a modified form of rivet 30a is shown, the rivet head 32a is offset as in the Fig. 8 construction, and its outer end portion 33a is split for the insertion of the pull tab pintle. Upon such insertion, the split head is upset or deformed slightly thereby to permanently secure the pull tab to the rivet.

With the construction so far described it will be seen that the slider body is open-ended, having a relatively narrow tail opening for the entry and exit of the interlocked fastener elements, and

with two head openings for the entry and exit of the disengaged fastener elements, of which one opening extends between one side of the connector 18 and the related side flange 20, and the other extends between the other side of the connector and the other side flange 21. Said side flanges, in conjunction with the underfaces of the plates 16, 17 of the slider and the sides of the separator 25, form a Y-shaped race for the fastener elements having a relatively lower straightway portion for the interlocked fastening elements, which in width corresponds to the length of two interlocked elements plus sliding clearance, and outwardly diverging branch portions, each opening through a head opening and having a width corresponding generally to the length of one fastener element plus sliding clearance. However, due to the bell-shaped contour of the plates, the race branches are outwardly bulged and are wider in the region of the intersection of the outwardly diverging and upper straightway portions of the side flanges, and hence at their intermediate portions, than at their end portions. Accordingly, while the fastener elements normally follow a straight line path of travel in moving through the race branches, as indicated in Fig. 2, the elements then disposed in the intermediate wider portion of each race branch are permitted lateral or relative outward movement when the stringers are subjected to lateral stress through the slider body, this for the purpose to be hereinafter discussed. With the elements normally having straight line movement through the race branches, as when the slider body is moved downwardly to open the fastener, the disengaged fastener elements are spread fanwise, and thus the slider body so far described is of standard design as respects its general shape and ability to dispose the disengaged fastener elements fanwise.

Considering now one of the improved self-locking features of the present slider, the straightway portions of the side flanges to the side of each head opening are sloped inwardly or towards the plane of the underfaces of the plates from which they extend. This will be seen from Figs. 5 and 7, wherein related or paired side flanges 20, 21 are sloped as at 20a, 20b and 21a, 21b so that paired flanges form a downwardly pointed funnel or V-shaped side opening adjacent each head opening of the slider body, said side openings at their wide end having width corresponding to the spacing between the slider plates and converging to a narrow end of lesser depth than that of the fastener elements. As shown, the flange sloping as aforesaid extends from about the junction of the diverging and upper straightway portions of the flanges to the upper plate corners, at which points the side flanges merge into the underface of their plates. The relatively inner edges of the sloping flange portions provide more or less flaring rounded corners (see Fig. 6) against which the adjacent fastener elements are adapted to interlock when the stringers are subjected to lateral stresses applied just above or through the upper region of the slider. Moreover, by reason of the V or funnel-shaping of the side openings, fastener elements tending to spread outwardly adjacent thereto are caused to move against the V-shaped locking edges defining the side openings and in some cases downwardly into the pointed ends of the openings and are accordingly jammed or wedged thereinto. Hence, by the above-described arrangement of

side locking openings, the slider positively locks with adjacent fastener elements as the latter tend to move outwardly under the influence of strains tending to spread the fastener, and unintentional movement of the slider under the aforesaid condition of stress is precluded.

In addition to the locking side openings as described, the present invention provides additional locking or fastener elements within the race itself, when such is required, and to this end the depth of the wider, intermediate portion of each race branch is reduced along the relatively outer side edge thereof, in relation to its normal depth which is that required for free sliding of the fastener elements therethrough, to the end that adjacent fastener elements tending to move outwardly under lateral stresses applied through the slider body and particularly through the upper half of the slider, are wedged within and thereby frictionally held by the race branch portions of reduced depth. This reduction in the depth of the race branches along the outer side edges of their intermediate portions is preferably accomplished through the provision of definitely rounded flaring corners, as distinguished from right angled corners, between the underfaces of the plates and the inner faces of the flanges extending therefrom. The rounded cornering is most pronounced at about the junction of the diverging and sloping portions of the side flanges, being indicated by the heavy shade lines at the points designated *a*, *b*, *c* and *d* in Fig. 3, and by the similarly designated cornering indicated in cross section in Fig. 7. From said points of extreme rounding, the corners diminish in curvature towards the head openings until, at their extreme upper corners, the plates are perfectly flat (see Fig. 6) as required for free sliding movement of the disengaged fasteners into and out of the race branches. Thus, with the widened intermediate portions of the race branches being of lesser depth along their outer sides, and preferably just slightly less than the depth of the fastener elements moving through the race, adjacent fastener elements tending to move outwardly frictionally bind against the slider body so that relative movement between the body and the so held fastener elements is precluded.

By reason of the shape of the slider race as described, the provision of the funnel-shaped side opening adjacent each head opening as well as of the definitely rounded cornering *a*, *b*, *c*, *d* provided within the fastener race, the slider is rendered inherently self-locking. This will be appreciated from a consideration of Fig. 2, from which it will be seen that longitudinal stresses applied to the fastener tend to straighten out the fastener elements as they branch to the sides of the separator 25. Under this condition the relatively inner ends of the interlocking elements tend to bind against the sides of the separator with sufficient friction that movement of the slider in opening direction is precluded.

When the fastener is subjected to lateral stresses applied just above the slider, for example, the fastener elements adjacent the funnel-shaped openings to the side of the head openings tend to ratchet with the inner corners of said openings and/or to be wedged into the more or less pointed ends of said openings with substantial friction and binding engagement. Accordingly opening movement of the slider under this condition of stress is prevented.

When the fastener is subjected to lateral

stresses applied directly through the slider, as would cause disengaged fastener elements to the sides of the separator 25 to move relatively outwardly, the fastener elements tend to bind against the definitely rounded corners *a*, *d* or *b*, *c*. When it is considered that such rounded cornering is formed on both the upper and under plates of the slider, and that the cornering results in the reduction in the depth of the race 10 branches in the region of the cornering, the aforesaid engagement of fastener elements therewith is accompanied by a binding or wedging action, with the result that the slider is definitely locked to the so-bound fastener elements and its 15 movement relative thereto is prevented.

Despite the effective self-locking provided by a slider constructed as in the foregoing, the slider is easily released irrespective of whether or not the fastener is under strain due to the fact that 20 both the funnel-shaped side openings and the curved cornering act in reverse manner to effect release when the slider is moved downwardly, for example, to disengage the fastener elements. This will be appreciated upon considering that 25 movement of the slider downwardly causes the sloped ends 20a, 20b and 21a, 21b of the flanges to cam fastener elements tending to interlock therewith relatively inwardly. The same is true of the curved cornering portions *a*, *b*, *c* and *d* 30 which, upon movement of the slider downwardly serve as cams forcing fastener elements tending to bind thereagainst in an inward direction. When cammed inwardly as aforesaid, the fastener elements are free to move through the race 35 branch portions in normal manner.

Accordingly, the present invention provides a self-locking slider of more or less standard contour and design, while at the same time providing a self-locking slider of the stated characters 40 which is of improved and commercially practical form. Such a slider is capable of production and assembly by known automatic and semi-automatic machinery and hence is available for immediate production without requiring retooling for its manufacture. Moreover, sliders in accordance with the invention possess relatively great structural strength by reason of the separator construction which functions cumulatively with the connecting bridge 18 to maintain the 50 slider plates in their intended parallel relation, even under crushing pressures that would impair if not destroy sliders manufactured by the known processes. This resistance to crushing pressure results to a large degree from the relatively large area abutment surfaces provided by the elliptical formation of the separator half-sections and the spacing of the separator from the connecting bridge in the direction of the geometrical center of the slider body.

As many changes could be made in carrying out the above constructions without departing from the scope of the invention, it is intended that all matter contained in the above description or shown in the accompanying drawing shall be interpreted as illustrative and not in a limiting sense.

I claim:

1. A self-locking slider for slide fasteners comprising spaced plates having depending side flanges, and a separator spacing said plates and forming with the plates and side flanges an elongated race for the fastener elements having diverging branch portions disposed to the sides of the separator whose normal width and depth is that required for free sliding movement of the

elements therethrough, said plates for a portion of their height being of greater width than that required to provide race branch portions dimensioned as aforesaid and being sloped towards each other to their flanges to provide outer branch lengths of reduced depth into which the outer ends of the fastener elements, which latter tend to move outwardly from said branch portions of normal depth under the influence of lateral stress applied through the fastener, are wedged and thereby locked to the slider.

2. A self-locking slider for slide fasteners comprising spaced plates having depending side flanges, and a separator spacing said plates and forming with the plates and side flanges an elongated race for the fastener elements having diverging branch portions disposed to the sides of the separator whose normal width and depth is that required for free sliding movement of the elements therethrough, said plates for a portion of their height being of greater width than that required to provide race branch portions dimensioned as aforesaid, the under faces of the extra-wide portions of said plates merging into the inner surfaces of their depending side flanges in such manner as to provide outer branch lengths of reduced depth into which the outer ends of the fastener elements, which latter tend to move outwardly from said branch portions of normal depth under the influence of lateral stress applied through the fastener, are wedged and thereby locked to the slider.

3. A self-locking slider for slide fasteners comprising spaced plates having depending side flanges, and a separator spacing said plates and forming with the plates and side flanges an elongated race for the fastener elements having diverging branch portions disposed to the sides of the separator whose normal width and depth is that required for free sliding movement of the elements therethrough, said plates for a portion of their height being of greater width than that required to provide race branch portions dimensioned as aforesaid, the under faces of the extra-wide portions of said plates being connected to the inner faces of the depending side flanges by rounded corners, thereby to provide outer branch portions of reduced depth into which the outer ends of the fastener elements, which latter tend

to move outwardly from said branch portions of normal depth under the influence of lateral stress applied through the fastener, are wedged and thereby locked to the slider.

5. A self-locking slider for slide fasteners comprising spaced plates having depending side flanges, a separator spacing said plates and forming with the plates and side flanges thereof an elongated race for the fastener elements having diverging branch portions disposed to the sides of the separator, the upper ends of the related side flanges cooperating to provide locking corners for locking with disengaged fastener elements tending to move sidewardly in emerging from the slider under the influence of the component of lateral stress applied to the fastener above and through the upper end of the slider, and said plates cooperating along a substantial portion of their length to provide a race portion of depth less than that of the fastener elements for locking disengaged fastener elements then within the race branch portions and which tend to move outwardly within the race in response to the component of lateral stress applied through the slider proper.

15. A self-locking slider for slide fasteners comprising spaced plates having depending side flanges, a separator spacing said plates and forming with the plates and side flanges thereof an elongated race for the fastener elements having diverging branch portions disposed to the sides of the separator, the upper ends of the related side flanges being oppositely inclined with reference to each other to provide V-shaped locking edges at the upper outer corners of the slider for locking with disengaged fastener elements tending to move sidewardly in emerging from the slider under the influence of the component of lateral stress applied to the fastener above and through the upper end of the slider, and said plates having extra width for a portion of their length and under faces in said extra-wide portion which slope towards each other to their side flanges thereby to provide race portions of reduced depth into which the fastener elements then within the race tend to wedge in moving outwardly in response to the component of lateral stress applied through the slider proper.

LOUIS W. SCHAAFF.
